His Attorney

UNITED STATES PATENT OFFICE

2,596,506

ELECTRIC CIRCUIT BREAKER

Robert G. Page, New Britain, Conn., assignor, by
mesne assignments, to General Electric Company,
a corporation of New York

Application December 21, 1950, Serial No. 201,943

6 Claims. (Cl. 200—166)

1

My invention relates to circuit breaker units and particularly to the contacts of a unit which is designed to be detachably mounted on a panel board or the like.

One object of the invention is to provide for a resiliently supported contact.

A special object is to provide for a contact structure adapted to be detachably supported on a fixed base.

One object is to provide a compact and effective structure.

Another object is to provide an economical structure consisting of few and simple parts.

Another object is to provide a structure which is easy to assemble.

Another object is to provide a structure having good arc-interrupting ability.

Another object is to provide a structure which is highly resistant to mechanical shock.

Another object is to guard the resiliently mounted contact structure from arcing.

Fig. 1 is a side view and partial section showing the contacts of a circuit breaker embodying my invention as applied to a panel board or other support.

Fig. 2 is a sectional view on a larger scale, the section being taken on the plane of the line 2—2 of Fig. 1.

Fig. 3 is a perspective view showing parts of the contacts of Figs. 1 and 2.

Fig. 4 is a perspective view of a reinforcing spring.

Fig. 5 is a side view showing the rock shaft, the switch arm being shown in section.

Fig. 6 is a perspective view of one end of the rock shaft.

Fig. 7 is a perspective view of the switch arm.

The insulating support 1, constituting a part of a panel board or other support, has a circuit terminal 2 with a projecting terminal prong or blade 3.

The circuit breaker has an insulating base, a part 4 of which is shown in Figs. 1 and 2. The relatively stationary jaws 5, 6 and 7 are formed as a part of the terminal structure 3 which is secured to the base 4 by a screw 9. The jaws are preferably formed of resilient material so that they will clamp the opposite sides of the panel blade 3 when the circuit breaker is mounted on the panel.

An insulating cover plate 10 is secured to the terminal structure 3 by suitable means such as the rivets 11. The contact member 12 is in the form of a cup which is mounted in a passage 13 in plate 10 and has a flange portion 14 beneath the plate 10. The contact surface 15 may be

2

separately formed of suitable material and attached to or made a part of the contact cup 12. A spring 16 is interposed between the insulating support 17 and the cup 12. The contact cup is electrically connected to the structure 8 by flexible conductors 18, 19.

The cover plate 10 of insulating material guards all of the contact structure except the contact 15 which, of course, must be exposed.

10 The contact 20 is carried by the arm 21 and coacts with the relatively stationary contact member. The lever 21 constitutes the movable switch member of the circuit breaker and is mounted on a shaft 22 of the rocker mechanism (not shown). The shaft 22 may be enclosed in an insulating sleeve 23. The switch arm 21 has a collar 24 drawn from the metal of the arm to receive sleeve 23. The extension 25 is secured to the shaft 22 by a set screw 26 and constitutes the means for transmitting motion from the circuit breaker mechanism (not shown).

15 The switch arm 21 is connected electrically to a terminal of the circuit breaker (not shown) by means of a flexible conductor 27. The use of an edgewise mounted blanked switch arm permits a close assembly of adjacent parts.

20 The contact jaws 5, 6 and 7 may be reinforced by a spring clamp member 28 having a cross-piece 29 compressing against the spring jaw 5 and having end members 30, 30 pressing against the back of the jaws 6 and 7.

25 From the foregoing it will be seen that the contact 15 is pressed toward the contact 29 by the action of the spring 16, but the movement of the contact member 12 is limited by the engagement of the flange 14 beneath the insulating plate 10. It will be understood that the operating and tripping mechanism and overload devices of a circuit breaker will function in a conventional manner.

30 The spring-pressed contact member 12 acts as a buffer for the switch arm and holds the circuit closed in case the switch arm should become loose.

35 I claim:

1. In an electrical circuit breaker, a lower fixed terminal blade, an upper movable switch arm and a contact unit between said blade and switch arm including a body portion of strip metal having 40 downwardly extending spaced contact jaws formed on one end thereof for engaging said terminal blade and having an offset portion formed on the opposite end, an insulating plate secured to said offset end and extending parallel to said body portion in spaced relation, a movable con-

tact member guarded by said insulating plate, a flexible conductor connecting said body portion and said movable contact member, and a spiral spring between said body portion and said movable contact member for urging said movable contact member into engagement with said upper switch arm.

2. In an electrical circuit breaker, a lower fixed terminal blade, an upper movable switch arm and a contact unit between said blade and said switch arm including a body portion having a plurality of spaced resilient contact jaws depending from one end thereof for engaging the terminal blade, an insulating plate mounted on said body portion, an upwardly extending movable contact member carried by said insulating plate and spaced from said contact jaws for engaging said switch arm, a flexible conductor connecting said body portion and contact member, and spring means in the space between said body portion and said movable contact member for urging the latter into engagement with said switch arm.

3. In an electrical circuit breaker, a lower fixed terminal blade, an upper movable contact member and a contact unit between said blade and contact member including a body portion having a plurality of spaced resilient contact jaws depending from one end thereof for engaging the terminal blade, an insulating plate mounted on said body portion and having an opening, an upwardly extending movable contact member extending through the opening in said insulating plate for engaging said upper movable contact member, a flexible conductor connecting said body portion and said contact member, and spring means for urging said upwardly extending contact member into engagement with said upper movable contact member.

4. As an article of manufacture, an electrical contact unit for use with a circuit breaker, comprising a flat body portion of strip metal, a pair of parallel resilient jaw members depending from one end of said body portion and another jaw member offset from said pair for engaging a switch blade, the opposite end of said body portion being offset, an insulating plate secured at one end to said offset end of the body portion and extending along the remainder of the body portion in spaced relation, a switch member movably supported at the other free end of the in-

sulating plate, a conductor connecting said body portion and said switch member, a spiral spring in the space between the body portion and insulating plate for urging said switch member upwardly, and a spring encircling said jaws for urging the jaws toward each other in a clamping action.

5. As an article of manufacture, an electrical contact unit for use with a circuit breaker, comprising a body portion, spaced resilient contact jaws depending from one end of said body portion for engaging a terminal blade, a movable contact member supported on the body portion and spaced from the contact jaws, a flexible conductor connecting said body portion and contact member, and spring means in the space between said jaws and said movable contact member for urging the latter into engagement with a switch arm.

20 6. As an article of manufacture, an electrical contact structure, for use with a circuit breaker, comprising a flat body portion of strip metal having a pair of spaced resilient parallel jaws depending from one end thereof and having another resilient jaw between said pair and offset therefrom for receiving a blade between said jaws, said body portion having an offset portion at its other end, a flat insulating plate secured at one end to said offset portion and extending over said body portion in spaced relation, a cup-shaped contact member movably mounted in the other end of said insulating plate for engaging a switch arm, a flexible conductor connecting said body portion and contact member, and a spiral spring having one end seated on the body portion and its other end seated in said cup-shaped contact member for urging said cup-shaped contact member outwardly of the insulating plate support into engagement with the switch arm.
